UNITED STATES PATENT OFFICE.

GEORGE D. PAUL, OF ORANGE, ASSIGNOR OF ONE-HALF TO ANDREW R. MILLER, OF EAST ORANGE, NEW JERSEY.

BRAKE FOR CHILDREN'S CARRIAGES.

SPECIFICATION forming part of Letters Patent No. 293,351, dated February 12, 1884.

Application filed May 8, 1883. (No model.)

To all whom it may concern:

Be it known that I, GEORGE D. PAUL, of Orange, in the county of Essex and State of New Jersey, have invented certain new and useful Improvements in Brakes for Children's Carriages; and I do hereby declare the following to be a full, clear, and exact description of the invention, such as will enable others skilled in the art to which it appertains to make and use the same.

My invention relates to an improvement in brakes for children's carriages, the object of the same being to provide mechanism whereby the brakes are released when the attendant grasps the push-rod, and automatically set when the push-rod is released, thereby preventing numerous accidents that are continually occurring by reason of carriages running off sidewalks when they are left temporarily by the parties in charge of them; and with these ends in view my invention consists in the parts and combinations of parts, as will be more fully described, and pointed out in the claim.

In the accompanying drawings, Figure 1 is a view in side elevation of a carriage embodying my invention. Fig. 2 is a perspective view of the rear axle, wheels, and push-rod, together with the braking mechanism. Fig. 3 is a detached perspective view of one of the brake-arms, and Fig. 4 represents a modification.

A represents the body of the carriage, and B the rear axle, to which the handle-bars C are removably or rigidly secured, as desired. These handle-bars are of the ordinary shape and construction, and are connected together at their outer ends by the push-rod D, which latter is also of the ordinary construction.

To the handle-bars C, and in line with the periphery of the wheels E, are pivotally secured the brake-levers F, which latter are provided with bifurcated inner ends, through which the bolts *a* pass for the purpose of pivotally securing them to the handle-bars. The outer ends of the levers F are considerably reduced in size, and are each provided with a brake-shoe, G, the inner face of which can, if desired, be covered with leather, wood, rubber, or other suitable substance for the purpose of producing the necessary friction between

the shoes and the wheels. As most wheels have more or less side or wobbling movement, the brake-shoes should either be made wide enough so as to bear on the said wheels irrespective of their position or be provided with side flanges, *b*, which would prevent the wheels from moving sidewise beyond the brake-shoes, the latter method being preferable, as it presents a better finish to the carriage. The brake-shoes and brake-levers can be cast integral with or separate from each other, as desired.

H are spiral springs, the front ends of which are secured to the handle-bars, while their rear ends are secured to the brake-levers near the brake-shoes. The tendency of these springs is to force or pull the brake-shoes against the wheels and prevent the wheels from turning; but this tendency is overcome by the lever I, pivoted to the handle-bars behind the brake-levers. This lever I is shaped to conform somewhat to the curvature of the handle-bars, so as to present a neat appearance, and is pivotally secured to and rests against the inner faces of the said handle-bars. The upwardly-turned front ends of this lever are connected to the brake-levers by the metallic rods *c*, which latter pass over the handle-bars, and are connected to the brake-levers in such a position that sufficient leverage will be obtained without the exertion of much power. The lever I is pivoted near the front ends of its side arms by the screws or bolts *d*, and the rear bar or hand-rest, J, thereof rests in front or over the push-rod of the handle. This concavo-convex hand-rest conforms in shape to the push-rod, and is adapted to be held down in close contact thereby by the attendant in charge of the carriage. When the carriage is at rest and the handle released, the springs draw the brake-shoes firmly against the wheels, and consequently elevate the hand-rest J slightly above the push-rod. When it is desired to move the carriage, the attendant simply grasps the handles in the ordinary manner, and the pressure exerted thereon to move the carriage is sufficient to depress the hand-rest J and release the brake.

Instead of using springs and brake-levers, as before described, the brake-levers them-

selves can be made of spring metal, and perform their functions in a satisfactory manner.

In Fig. 4 I have shown a simple brake bar or lever provided at opposite ends with brake-shoes adapted to bear against the wheels. This bar is shown suspended from the handle-bars by spring-metal arms *e*; but it is evident that it can be held in suitable slide-bearings on the under side of the handle-bars, and the brake-shoes thereof be drawn against the wheels by spiral springs, as in the first instance. Again, all of my improved parts are attached directly to the carriage-handle, and hence, if the handle is a removable one, or one that can be secured to the front or rear axle, the brake mechanism is always in position to act directly on the wheels without the necessity of rearranging any of the parts.

My improved brake is simple in construction, is durable and effective in use, and can be applied to any and all styles of children's carriages without marring their beauty or materially increasing their cost.

It is evident that slight changes in the con-

struction and relative arrangement of parts 25 might resort to without departing from the spirit of my invention; and hence I would have it understood that I do not confine myself to the exact construction shown and described, but consider myself at liberty to make such 30 changes and alterations as fairly fall within the spirit and scope of my invention.

Having fully described my invention, what I claim as new, and desire to secure by Letters Patent, is—

The combination, with the wheels and handle of a child's carriage, of brake-operating levers *I I J*, pivoted at *d d* to the side arms of the carriage-handle, brake-shoes, rods *c c*, and springs *H H*, substantially as set forth.

In testimony whereof I have signed this specification in the presence of two subscribing witnesses.

GEORGE D. PAUL.
